DEVICE TO RAISE AND LOWER CURTAINS
AND DRAPE

Matthew Jenal, Brooklyn, N. Y.

Application September 22, 1934, Serial No. 745,136

1 Claim. (Cl. 156—27)

The invention relates to improvements as an accessory for use on a window frame to accommodate the dressing of a window for curtains or drapes. The invention illustrated in the drawing is for a domestic type of window.

It is a common practice to insert nails or screws through brackets to upper part of window frame to secure same and to accommodate one or two curtain rods. These curtain rods are adjustable, 10 detachably mounted to brackets on upper part of window frame. In mounting fixtures of this kind and to drape the window it means to climb to accomplish this task which is dangerous. With this device in mind it is possible to attach adjustable curtain rods at a low elevation and to raise the curtain rods to a desired point of elevation and to hold in this position until it is to be lowered for removal of curtain rods.

This invention is designed of suitable mechanical parts which there are eight devices, four pulley blocks, two cords and two pull rods. One form of the invention is illustrated in accompanying drawing in which Fig. 1 is a vertical front view of the entire device assembled. Fig. 2 is a 25 top plan view of device observed in Fig. 1. Fig. 3 is a vertical side view of the assembled device. Fig. 4 is a vertical front view of the device at its lowest elevation. Fig. 5 is an end view of one of the pulleys of the device.

In the drawing of Fig. 1 the window frame is 30 designated by the numeral 9; the horizontal dotted lines numeral 10—11 indicate the adjustable curtain rods at their lowest elevation.

In the drawing of pulley block 15 a hole is provided for shaft 20. On top of pulley block is a flange to accommodate fastener screw 16; below this flange is a dowel 17 extending from the pulley block, this dowel 17 pierces the wood and keeps pulley block from shifting, the drawing of two will suffice for the four.

In the pulley block 15 an eccentric pulley 21 is supported by shaft 20. Around these eccentric pulleys 21 is cord 18 supporting pull rod 13 by 10 two knots 19; these knots are for stops. Pull rod 13 floats between lower pulley block 15 and eccentric pulley 21. The upper pulley block 15 retains pull rod 13. Below the lower pulley block 15 extends the pull rod 13. This extension of pull 15 rod 13 is used as a finger grip 22. On the upper part of pull rod 13 between knots 19 is attached a rivet plate 14 supporting curtain rod bracket 12. This pull rod is in the form of a flexible strip provided with three holes to receive the cord 18 20 and rivet plate 14. Each turn of the eccentric pulleys 21, at one position thereof, binds cord 18 and thus retains the pull rod 13, therefore doing away with locks, anchor pins, etc.

I claim:

The combination with a pair of vertically spaced pulley blocks each having an eccentric pulley mounted therein, of a flexible pull rod supporting bracket and a cord around said pulleys supporting said flexible pull rod in a vertical position from a point between said pulleys.

MATTHEW JENAL.
